UNITED STATES PATENT OFFICE

WALTER H. SERGENT, OF MIDDLETOWN, NEW YORK, ASSIGNOR TO IDEAL WRAPPING MACHINE CO., A CORPORATION OF NEW YORK

SUCKER-IMPALING MACHINE

Application filed January 19, 1927. Serial No. 162,197.

This invention relates to a sucker impaling machine and concerns itself with a structure in which a plurality of wrapped suckers packed in a suitable box or container may be 5 simultaneously impaled.

The invention comprises the novel structure and combination of parts hereinafter described and more particularly pointed out and defined in the appended claims.

10 In the accompanying drawings which illustrate a preferred embodiment of this invention and in which similar reference numerals refer to similar features in the different views:

15 Figure 1 is a side elevational view of a sucker impaling machine involving this invention.

Figure 2 is a top plan view of the same.

20 Figure 3 is an enlarged vertical sectional view of the same.

Figure 4 is a view similar to Figure 3 showing parts in different positions.

Figure 5 is a front elevational view of the 25 machine with parts omitted.

Figure 6 is an enlarged sectional view taken upon the line VI—VI of Figure 1 with the impaling sticks removed.

Figure 7 is an enlarged sectional view upon 30 the line VII—VII of Figure 1 showing parts in elevation.

Figure 8 is an enlarged fragmentary sectional view of the stick magazine.

Figure 9 is an enlarged fragmentary sectional view taken upon the line IX—IX of 35 Figure 6.

As shown on the drawings:

As illustrative of this machine there is 40 shown a frame comprising a supporting base 1 from which there extends a vertical standard 2, having a laterally extending top 3 which overhangs the base portion 1. The base 1 is provided with means for securing a plurality of wrapped suckers. The suckers are preferably contained in a regular packing box ready 45 for the market. In the form shown this means consists of a boxlike structure having a stationary side 4 (Figure 7) to which a pair of ends 5 are hingedly connected by 50 pivots 6. The side 7 opposite the side 4 is

adjustably supported upon a pair of studs or bolts 8 which are secured in the bottom 9 of the box. The ends of the side 7 are beveled as indicated at 10 for cooperating with beveled blocks 11 on the end members 5. Suitable latch members 12 are pivoted upon the ends of the bottom 9 of the box by means of pivots 13. The ends of these latches are beveled for engaging triangular wedge members 14 on the end members 5. The aforementioned latches 12 are provided with handles 15 which extend at right angles to the wedge portion as shown more clearly in Figure 1. When the handles are in horizontal position as shown in Figures 1 and 7, the end members 5 are latched in operative position. However, if the handles 15 are swung into lowered vertical position as shown in dotted lines in Figure 1, the latch members 12 will be swung clear from the ends of the members 5 and will lie adjacent the ends of the bottom 9 of the box. In this position the end members 5 may be swung outwardly and the member 7 may slide outwardly on its pivots 8 so that the box of suckers may be placed therein. The end members 5 may then be swung inwardly and the latches 15 may be swung into operative position for engaging the end members 5 and blocks 14. As the end members 5 are swung inwardly the blocks 11 will engage the sloping portions 10 of the movable side member 11 and draw the same inwardly against the side of the container.

From the aforementioned base there extends a pair of guide rods or posts 16 upon which a cross-head 17 is mounted for reciprocation. A plate 18 is secured upon the bottom of the cross-head 17 and together therewith constitutes the striker or driver for impelling the sticks into the suckers. A pair of transverse beams or supports 19 are secured on the top of the driver 17 and each transverse member 19 has suspended therefrom a pair of guide rods 20. These guide rods 20 are slidably supported in the transverse members 19 and are suspended from the nuts 21. The lower ends of the rods 20 sustain a stripper plate 22 and suitable coil springs 23 are confined between the stripper plate 22 and the 100

transverse members 19 for a purpose that will later appear.

Beneath the cross-head or driver 17, there is a second pair of transverse members 24 which are secured for movement therewith. With reference to Figure 5, it will be noted that the transverse members 24 are shorter than the transverse members 19 and are slightly inside of the planes thereof. Each of these second transverse members slidably supports a pair of rods 25, the upper ends of the rods being confined by suitable nuts 26. The lower ends of the rods 25 sustain a plate 27 which forms a support for the stick magazine 28 (Figure 6). The stick magazine 28 is slidably retained upon its base support by the lateral guide members 29 and 30 which are suitably undercut as shown in Figures 3 and 4 to receive the margins of the magazine thereunder. It might be here mentioned that the sustaining rods 25 are secured to these guide members 29 as shown in Figure 6. Upon the rear end of the support 27 there is secured a block 31 (Figure 9) which limits the inward sliding movement of the stick magazine. It might be mentioned that the stick magazine 28 may be slid upon its support under the aforementioned guides from the upper end as viewed in Figure 6 and when it abuts the block 31 it may be latched in position by a latch member 32 which is pivoted upon suitable ears formed on the block 31. The inner end of the latch 32 is provided with a detent 33 which engages a suitable slot or recess 34 formed in the stick magazine. In the present instance it will be seen that the stick magazine is provided with a recess in which a small block 35 is secured in spaced relation from the inner wall of the recess and the detent 33 fits between the block 35 and the inner wall of the recess. It will be noted that the stick magazine and its support 27 are provided with suitable registering apertures 36 and 37 respectively when the same are in assembled relation. Each aperture in the stick magazine contains a small tube or barrel 38 which is shown in detail in Figure 8. Each tube has a slot 39 cut through one wall thereof and a leaf spring 40 is secured to each tube adjacent the slot and each spring has a deformed or V-shaped portion 41 which extends into the thoroughfare through the tube. The function of these springs is to frictionally retain the impaling sticks 42 therein as shown in Figure 3. It will also be noted that the afore-described stripper plate 22 is provided with apertures which are in register with the thoroughfares through the stick magazine. The means for imparting reciprocating motion to the cross-head 17 will now be described. With reference to Figures 3 and 4, it will be noted that a rack bar 43 is secured to the cross-head or driver 17 and extends through a suitable guideway 44 in the over-

hanging head 3 of the frame. The rack 43 meshes with a pinion or gear 45 which is journaled upon a shaft 46 which extends through a semi-circular recess upon one side of the guideway 44. The ends of the shaft 46 are journaled in suitable bearings 47 and 48 (Figure 5) integral with the head 3. Upon one end of the shaft there is secured a handwheel 49 and upon the other end of the shaft there is secured a ratchet wheel 50. A manually actuated pawl 51 is pivoted upon the frame for engagement with the ratchet wheel 50 for preventing the same from rotating when the stick magazine is in elevated position.

In the operation of this sucker impaling machine, a box or container of wrapped suckers is positioned in the form or box at the base of the machine, and clamped in impaling position as previously explained. The stick magazine may then be removed from its support and replenished with sticks which need only to be inserted in the tubes where they will be frictionally retained by the springs 40. The stick magazine may then be replaced upon its support and latched thereto by the latch 32 as previously explained. The operator will then elevate the pawl 51 and rotate the handwheel 49 for causing the driver 17 to descend. When the driver 17 has descended a sufficient distance, the stripper plate 22 will come to rest on the top of the wrapped suckers which are indicated by the reference numeral 52 in Figures 3 and 4. Thereafter the driver 17 will move relatively to the stripper plate 22 and compress the springs 23 until the stick magazine rests upon the top of the stripper plate as shown in dotted lines in Figure 3. Thereafter the driver 17 will move relatively to the stick magazine until the striker plate 18 engages the tops of the impaling sticks 42 and forces the same within the wrapped suckers.

After the suckers have been properly impaled, the operator will, of course, rotate the handwheel in the opposite direction for elevating the various parts. During this reverse operation the driver 17 will first be elevated until the transverse members 24 engage the nuts 26. Thereafter the stick magazine will travel upwardly with the driver 17 and become disengaged from the impaling sticks 42 through the instrumentality of the stripper plate 22 which is still being yieldingly retained against the top of the suckers by the springs 23. As soon as the impaling sticks are stripped from the magazine and the driver 17 has been elevated until the transverse members 19 engage the nuts 21 on the stripper rods 20, the stripper plate will be elevated with the driver 17.

From the foregoing it will be obvious that a very simple machine has been provided whereby a large number of wrapped pieces

of candy or suckers may be simultaneously impaled with very little effort. It will also be noted that the difficulty of wrapping the suckers after they are impaled is avoided by the present machine. According to this invention the suckers may be properly wrapped in large quantities in a suitable machine. The wrapped suckers may then be packed in a suitable container which fits in the box or clamping form at the base of the machine. Obviously, a great deal of time and labor is saved by the use of this machine.

I am aware that many changes may be made and numerous details of construction may be varied through a wide range without departing from the principles of this invention and I, therefore, do not purpose limiting the patent granted hereon, otherwise than necessitated by the prior art.

20 I claim as my invention:

1. In a sucker impaling machine, the combination with means for securing a plurality of suckers, of means for simultaneously guiding and positioning a plurality of impaling sticks with respect to said suckers, and a reciprocable member for simultaneously driving said sticks into said suckers and means for stripping said sticks from said second-mentioned means.

20 2. In a sucker impaling machine, means for securing a plurality of suckers in impaling position, reciprocable mechanism embodying a stick magazine for carrying and positioning a plurality of sticks with respect to said suckers, a device for driving said sticks into said suckers, and means for stripping said sticks from said magazine.

30 3. In a sucker impaling machine, means for securing a plurality of suckers in impaling position, a stick magazine for simultaneously positioning a plurality of sticks with respect to said suckers, said magazine frictionally retaining said sticks against slidable movement, and a movable striker movable with and relative to said stick magazine for simultaneously driving said sticks into said suckers.

40 4. In a sucker impaling machine, means for securing a plurality of suckers in impaling position, a reciprocable stick magazine for simultaneously positioning a plurality of sticks with respect to said suckers, a reciprocable striker for simultaneously driving said sticks into said suckers, and a stripper plate for acting against said impaled suckers while said magazine is receding for stripping the sticks therefrom.

50 5. In a sucker impaling machine, means for securing a plurality of suckers in impaling position, a reciprocable stick magazine adapted for positioning a plurality of impaling sticks with respect to said suckers, a stripper plate movable in advance of said magazine until it rests upon said suckers, means for driving said sticks into said suckers, and yielding means for maintaining said

stripper upon said suckers while said magazine recedes a predetermined distance for stripping the sticks therefrom.

6. In a sucker impaling machine, means for securing a plurality of suckers in impaling position, a reciprocable striker, and a stick magazine slidably connected to said striker for positioning a plurality of sticks with respect to said suckers during the operative movement of said striker, said striker and magazine having relative movement when the former reaches a predetermined position.

7. In a sucker impaling machine, a reciprocable striker, a stick magazine and a stripper plate connected to said striker for relative movement with respect thereto.

8. In a sucker impaling machine, a reciprocable striker, and a stick magazine movable with said striker and having relative movement thereto.

9. In a sucker impaling machine, a reciprocable striker, a stick magazine connected to said striker for relative movement, and a stripper plate in advance of said magazine connected to said striker for relative movement.

10. In a sucker impaling machine, means for securing a plurality of suckers in impaling position, a reciprocable striker, a stick magazine and a stripper plate connected to said striker for relative movement with respect to each other when said stripper plate contacts said suckers.

100 11. In a sucker impaling machine, a reciprocable striker, a stick magazine having supporting rods slidably supported with respect to said striker, a stripper plate in advance of said magazine having supporting rods slidably supported in said striker, and coil springs between said striker and stripper plate.

110 12. In a sucker impaling machine, a striker a stick magazine, rods connecting said magazine and striker for relative movement, a stripper plate in advance of said magazine, rods connecting said plate and striker for relative movement, and coil springs surrounding the last mentioned rod and abutting said striker and stripper plate.

115 13. In a sucker impaling machine, a retaining frame for securing a box of suckers, said frame having an adjustable side and a pair of swingable ends, said adjustable side and ends having coacting sloping parts adapted to be brought into coaction when said ends are swung to closing position.

120 14. In a sucker impaling machine, a box retaining frame having an adjustable member and a swingable member and a latch for securing said swingable member in operative position, said adjustable member and swingable member having coacting sloping ends adapted for wedging rotation.

125 15. In a sucker impaling machine, a re-

ciprocable striker, a support connected to said striker and a stick magazine removably carried by said support.

16. In a machine of the character described, a stick magazine comprising a supporting base having aperatures, a stick holder removably mounted upon said base and having apertures adapted to register with the apertures in said base and means for clamping said stick holder to said base with the apertures in registry.

17. In a sucker impaling machine, means for retaining a plurality of suckers in impaling position, a stick magazine for positioning a plurality of sticks with respect to said suckers, a driver for simultaneously driving said sticks into said suckers, and means for stripping said sticks from the magazine during the withdrawal thereof.

18. In a sucker impaling machine, means for retaining a plurality of wrapped suckers in impaling position, a reciprocable stick magazine for positioning a plurality of sticks with respect to said wrapped suckers, a combined guide and stripper plate movable in advance of said magazine and adapted for abutting said suckers, and a striker for simultaneously driving said sticks into said suckers.

30. In testimony whereof I have hereunto subscribed my name.

WALTER H. SERGENT.
